CLAIM

We claim the ornamental design for the security tag holder, as shown and described.

DESCRIPTION

FIG. 1 is a perspective illustration of a first embodiment of a security tag holder shown in a configuration of use; FIG. 2 is a rear perspective illustration of the security tag holder of FIG. 1; FIG. 3 is a front view of the security tag holder of FIG. 1; FIG. 4 is a rear view of the security tag holder of FIG. 1; FIG. 5 is a first side view of the security tag holder of FIG. 1; FIG. 6 is a second side view, opposite the first side view, of the security tag holder of FIG. 1; FIG. 7 is a top view of the security tag holder of FIG. 1; FIG. 8 is a bottom view of the security tag holder of FIG. 1; FIG. 9 is a perspective illustration of a second embodiment of a security tag holder shown in a configuration of use; FIG. 10 is a rear perspective illustration of the security tag holder of FIG. 9; FIG. 11 is a front view of the security tag holder of FIG. 9; FIG. 12 is a rear view of the security tag holder of FIG. 9; FIG. 13 is a first side view of the security tag holder of FIG. 9; FIG. 14 is a second side view, opposite the first side view, of the security tag holder of FIG. 9; FIG. 15 is a top view of the security tag holder of FIG. 9; and, FIG. 16 is a bottom view of the security tag holder of FIG. 9.
 The broken line showing of a cylindrical object in figures 1 and 9 is included for the purpose of illustrating environment and forms no part of the claimed design. All other broken lines are included for the purpose of illustrating portions of the security tag holder and forms no part of the claimed design.
